UNITED STATES PATENT OFFICE.

ARTHUR W. F. STENZEL, OF NEW YORK, N. Y.

CHARACTERIZING ATTACHMENT FOR CAMERAS.

1,319,811.

Specification of Letters Patent.

Patented Oct. 28, 1919.

Application filed July 16, 1918. Serial No. 245,173.

To all whom it may concern:

Be it known that I, ARTHUR W. F. STENZEL, a subject of the Emperor of Germany, and residing at New York, in the county of 5 New York and State of New York, have invented certain new and useful Improvements in Characterizing Attachments for Cameras, of which the following is a specification, such as will enable those skilled in the art 10 to which it appertains to make and use the same.

This invention relates to cameras used both for pleasure and commercial use, and the object of the invention is to provide cameras of this class with characterizing attachments which will permit the operator or owner of the camera to give a suitable title to the picture taken, or about to be taken; a further object being to provide a camera 20 attachment of this class with a plurality of type characters or stencils which may be placed in a single or a plurality of lines or rows of type depending upon the length of the title given to the picture taken; and a 25 still further object is to provide an attachment of the class specified which is simple in construction and operation and efficient in use; and with these and other objects in view the invention consists in an apparatus of 30 the class specified, constructed and operating as hereinafter described.

The invention is fully disclosed in the following specification, of which the accompanying drawing forms a part, in which 35 the separate parts of my improvement are designated by suitable reference characters in each of the views, and in which:

Figure 1 is a plan view of the back of a camera showing my attachment applied 40 thereto;

Fig. 2 a partial section on the line 2—2 of Fig. 1 on an enlarged scale;

Fig. 3 a view similar to Fig. 2 but showing the parts in a different position and with 45 parts omitted;

Fig. 4 a section on the line 4—4 of Fig. 1 and on an enlarged scale, and with parts omitted;

Fig. 5 a sectional and perspective view of 50 a type supporting casing which I employ;

Fig. 6 a sectional and perspective view of one of a number of lock members employed in connection with the casing shown in Fig. 5; and,

Fig. 7 a perspective view of one of a number of type characters employed in connec-

tion with the casing shown in Fig. 5, and on an enlarged scale.

In Figs. 1 to 4 inclusive, I have indicated at 10 a camera case having a back 11 which 60 is provided at a predetermined distance from one end thereof with an elongated aperture 12.

In the practice of my invention, I secure to the walls of the aperture 12 an L-shaped 65 finishing-strip 13 to the bottom edge portion of which is secured a flexible strip 14 which is also secured to the bottom portion of the side walls 15 and end walls 16 of a type character supporting casing 17 which is 70 shown in detail in Fig. 5 of the drawing. The side and end walls 15 and 16 of the casing 17 are L-shaped in form in cross section, or are provided with inwardly directed base flanges 18, and said casing is provided centrally and longitudinally thereof with a T-shaped partition wall 19 which forms two corresponding compartments 20 and 21 in said casing at the opposite sides of the 75 wall 19.

A plurality of type characters or members 22, one of which is shown in detail in Fig. 7, are adapted to be inserted into and removed from the compartments 20 and 21 and rest on the flanges 18 and the oppositely directed base flanges 23 on the partition wall 19, and one side edge portion of each of said members 22 is rounded or made convex in form as shown at 24, while the opposite side edge is grooved or made concave in form as 90 shown at 25 in Fig. 7. With this construction the separate members 22 are placed adjacent to each other in the separate compartments 20—21 with the convex edges 24 of one member 22 in the concaved faces 25 of 95 another as indicated in Fig. 4 of the drawing. It will be understood that the type characters or members 20 are cut out to form characterizing symbols, and in Fig. 7 the member 22 is cut out as shown at 26 to form 100 the character J of the alphabet, and it will also be understood that in the use of my improvement a suitable receptacle will be provided for carrying a predetermined number of members 22 representing each letter of 105 the alphabet, the numerals from 1 to zero inclusive, and other signs, characters or the like that may be required.

Mounted beneath the aperture 12 in the back wall 11 of the camera case 10 is a 110 shutter slide 27 supported by side keepers 28 and the inner end portion of the shutter

slide 27 is provided with a bead 29, and the other end portion thereof passes through the camera case as shown at 30 and is provided with a downwardly directed finger piece 31 whereby the slide may be withdrawn from the casing as indicated in dotted lines in Figs. 1 and 4 and moved into the position shown in Fig. 4.

I also provide a suitable backing plate 32 which is secured to the opposite side walls of the camera case 10 as shown at 33, and between which and the shutter slide 27 the film 34 and film backing sheet 35 are adapted to pass from one spool of the camera to the other, and I also employ a guide roller 36 over which the film and backing sheets pass and which hold said sheets centrally of the slide 27 and backing plate 32, as clearly shown in Fig. 2 of the drawing.

20 The backing sheet 35 is provided at correspondingly spaced intervals with transparent or translucent strips 37 which are adapted to coöperate with the aperture 12 in the back 11 of the camera case when the film is in position to be exposed for taking a picture.

In the use of my attachment and before a film is connected or threaded through the camera, the shutter slide 27 is first moved 30 into the position shown in full lines in Figs. 2 and 4, and after the film has been put in proper position and the first film section moved into position to be exposed the same may be exposed, or the picture taken, after 35 which said picture may be given a suitable title, or may be characterized in any desired manner by placing the desired type characters or stencil members 22 in one or both of the compartments 20—21 when the 40 casing 17 is in the position shown in Figs. 2 and 4, after which a lock device 38 is placed in each of said compartments as clearly shown in Figs. 2 to 4 inclusive to retain the members 22 in proper position, 45 after which a cover or closure device 39 is placed upon the lock devices 38, as clearly shown in Figs. 1 and 2, and by grasping a handle or finger piece 40 secured centrally of the cover 39, the casing 17 with the members 22 and devices 38 connected therewith may be moved downwardly into the position shown in Fig. 3, after the shutter slide 27 has been moved into the position indicated 50 in dotted lines in Figs. 1 and 3, and the title 55 or character given to the picture about to be taken, or a picture that has been taken, may be produced by removing the cover 39 for a short time and again replacing it upon the casing 17, after which said casing may 60 be moved upwardly into the position shown in Fig. 2, and the shutter slide 27 moved into its full line position and the cover 39, devices 38 and member 22 removed to permit the insertion of other members 22 when 65 desired.

It will be understood that when only one compartment 20—21 is to be utilized for characterizing a picture taken, or about to be taken the other compartment will be closed by a strip or sheet, the dimensions of 70 which will correspond to that of the length and width of said compartment.

While I have shown the type characters or stencil members 22 as consisting of a sheet with the designating character or element 75 cut out therein, it will be understood that my invention is not limited to the use of this form of characterizing element. My invention is also not limited to the means for interlocking the type characters or designating members herein shown and described as this may be accomplished in any desired manner, nor is my invention limited to the specific form or arrangement of parts herein shown and described, and while I have 80 shown and described my attachment as applied to a camera employing a film, it will be understood that the same may be used in connection with cameras employing plates and the like, and various changes in and 85 modifications of the details of construction herein shown and described may be made, within the scope of the appended claims, without departing from the spirit of my invention or sacrificing its advantages. 90

Having fully described my invention, what I claim as new and desire to secure by Letters Patent, is:—

1. The combination with a camera of a casing mounted in one wall of said camera 100 and movable inwardly and outwardly therethrough, means for supporting a plurality of characterizing members in said casing, means for preventing the exposing of said members onto the film of the camera when 105 connecting the same with said casing, and means for preventing the exposure of said members onto the film when the last named means is removed.

2. The combination with a camera of a 110 casing mounted in one wall of said camera, said casing comprising a plurality of compartments adapted to receive characterizing members, means for retaining a plurality of said members in said compartments, means 115 for preventing the exposure of said members onto the film in their assemblage in said casing, means for preventing the exposure of said members when assembled and when said last named means is removed, and 120 means whereby said casing with the members mounted therein may be moved toward and from the film of the camera.

3. A characterizing attachment for cameras comprising a casing, means for supporting characterizing members in said casing, means for mounting said casing to move inwardly and outwardly through a wall of the camera case, a shutter device for controlling the exposure of the characterizing 125 130

- members in said casing and a cover or closure device for said casing.
4. A characterizing attachment for cameras, comprising a casing, means for supporting characterizing members in said casing, means for mounting said casing to move inwardly and outwardly through a wall of the camera case and to exclude light from said case in such movement, a shutter device for controlling the exposure of the characterizing members in said casing, a closure device for said casing, and means for supporting the film of the camera in the inward movement of said casing. 50
- 10 5. A characterizing attachment for cameras, comprising a casing, means for supporting a plurality of characterizing members in said casing, means for mounting said casing to move inwardly and outwardly through a wall of the camera casing to co-operate with the film or plate of the camera, means for supporting the film on the inward movement of said casing, and a shutter device for controlling the exposure of said characterizing members on said film. 55
- 15 6. A characterizing attachment for cameras, comprising a casing divided into a plurality of compartments, means for supporting a plurality of characterizing members in the compartments of said casing, said members being interlocked one with another, means for mounting said casing to move inwardly and outwardly through a wall of the camera case and to co-operate 60
- 20 with the film or plate of the camera, means for supporting the film on the inward movement of said casing, and a shutter device for controlling the exposure of said characterizing members on said film. 65
- 25 7. A characterizing attachment for cameras, comprising a casing divided into a plurality of compartments, means for supporting a plurality of characterizing members in the compartments of said casing, said members being interlocked one with another, means for mounting said casing to move inwardly and outwardly through a wall of the camera case and to co-operate with the film 70
- 30 8. A characterizing attachment for cameras, comprising means for supporting characterizing members in a wall of the camera, said supporting means being adapted to be moved inwardly and outwardly through said wall of the camera case, and a shutter device for controlling the exposure of the characterizing members in said supporting means. 75
- 35 9. The combination with a camera case having a longitudinal opening, and a film movable transversely of said opening and provided at intervals with transparent strips, of a characterizing attachment comprising a casing adapted to support a plurality of characterizing members, means for moving said casing with the members supported therein toward and from a transparent strip on the backing sheet of the film of the camera, and a shutter device for controlling the exposure of the characterizing members on the film. 80
- 40 10. The combination with a camera having a longitudinal opening in one wall thereof, and a film movable transversely of said opening, of means for supporting a plurality of characterizing members in said opening, means for preventing the exposure of said members on the film of the camera when connecting the same with said supporting means and other means for preventing the exposure of said members onto the film when the last named means is removed. 85
- In testimony that I claim the foregoing as my invention I have signed my name in presence of the subscribing witnesses this 13th day of July 1918. 90

ARTHUR W. F. STENZEL.
